UNITED STATES PATENT OFFICE.

JOHN S. SHERMAN AND ALVIN G. SHERMAN, OF DETROIT, MICHIGAN, ASSIGNEES TO DETROIT VAPOR STOVE COMPANY, OF DETROIT, MICHIGAN, A CORPORATION OF MICHIGAN.

PRIMING HORN.

Application filed February 20, 1922. Serial No. 537,864.

To all whom it may concern:

Be it known that we, JOHN S. SHERMAN and ALVIN G. SHERMAN, citizens of the United States, residing at Detroit, in the 5 county of Wayne and State of Michigan, have invented certain new and useful Improvements in Priming Horns, of which the following is a specification.

This invention relates to so-called vapor 10 stoves and has for its object an improved fuel and priming connection. The burner used in connection with this stove is intended primarily to burn kerosene or heavy hydrocarbon. In order to ignite kerosene 15 it has to be vaporized. Heat is necessary to vaporize kerosene and this is accomplished by first "priming" the burner.

In order to prime the vaporizer it is necessary to heat this before the kerosene or 20 heavy hydrocarbon is turned into it. This can be expeditiously done by introducing a little gasoline into the same and igniting it. This quickly heats up the vaporizer and when the kerosene or heavy hydrocarbon is 25 turned into the vaporizer, this vaporizes and burns with a steady smokeless flame. Of course, after the burner is once started the vaporizer becomes hot and serves to vaporize the fuel oil as fast as it can be consumed.

It is the object of the present invention to provide a priming connection which will be cheap and easy to manufacture and which will never become clogged with dirt 35 or other stuff. In prior Patents #1,149,300, Aug. 10, 1915, and #1,257,133, Feb. 19, 1918, issued on the applications of Alvin G. Sherman, there are described and claimed two priming connections, each employing a 40 partially open funnel. Each funnel had a slip joint connection with the member into which it introduced the priming fluid. These priming connections have been quite extensively used but they have been found 45 to be objectionable because they become clogged and for other reasons. The connection shown in Patent #1,257,133 included an ordinary T in the fuel line. After the fuel pipes were screwed into the 50 T, the pipe ends overlapped the priming port and this had to be bored out by putting a drill down through the top of the T. If the pipes and T were ever again disassembled for cleaning or otherwise, it was 55 practically impossible to again get the hole

in the pipe end to register with the priming port in the T.

The present priming connection obviates these various disadvantages by eliminating entirely the open funnel and affording a 60 T which has shoulders to keep the pipe ends away from the priming port. The T is combined in one casting with an elbow which takes the place of the funnel. We call the combined T and elbow a "priming 65 horn" for it very closely resembles a horn.

In the drawings,—

Fig. 1 is a plan view of the vaporizer and the priming and fuel connections.

Fig. 2 is a fragmentary section of a vapor burner showing the priming connection, part of the fuel line and a part of the burner.

Fig. 3 is a fragmentary longitudinal section of the priming horn.

Fig. 4 is a similar view showing the cover raised.

Fig. 5 is a perspective of the cover.

Fig. 6 is a section on the line 6—6 of Fig. 2.

Fig. 7 is a section on the line 7—7 of Fig. 1.

The burner is made up of a plurality of composite rings *a*, *b* and *c*. These rings have kerfs *d* sawed in one or more of the 85 walls of the composite ring. These kerfs form air inlets to let in the air to the combustion channels *e* which exist between the composite rings. These kerfs are sawed in the sides of the cast rings. The cast rings 90 are provided with reinforcing and spacing vertical ribs *f*. These composite rings *a*, *b* and *c* sit on a pair of channel rings *g* which form the vaporizer for the burner. These channel rings are connected so that, 95 in priming, the fluid or fuel oil running in the outer channel also runs into the inner channel. This much of the construction represents a well known type of wickless oil burner.

The nipple *h* is a part of the ring casting and is arranged to take the pipe *i* which screws into it and connects with the priming horn *j*. This is a special casting provided with a T head adapted to take the 105 pipe *i* and also the one end of the T *k*. This T *k* serves as a connection with the fuel oil main *m* and serves also as a valve casing. This T *k* supports the needle valve *n*, which is controlled by the handle *o*, and 110

the end of the T k that screws into the head of the priming T is plugged and provided with a relatively small opening which is regulated by the needle valve n . The priming horn T is provided with a pair of shoulders x , x , which limit the distance the pipe i and the T k may screw into the priming horn T . Hence these pipe ends can never overlap the priming port y .

10 The priming horn is a casting and is provided with a lug p on its top arranged to support a pin q which passes through the knuckles r rolled onto the forked end of the lid s . It will be seen that the front end of the horn is beveled off so that when the horn is in place, as shown in Fig. 1, with a slight inclination this bevel is on an inclination of almost 45 degrees to the vertical. This affords a suitable funnel into which the priming liquid may be poured and also affords a suitable seat for the gravity lid s . This lid can be raised easily with the finger and when in its raised position it will maintain itself (Fig. 4) because of the shoulder t between the forked or knuckle portions striking against the top of the lug p after the center of gravity of the lid has swung over the vertical rising from the fulcrum of the lid. This is portrayed in Fig. 4.

15 20 25 30 35 40 45 50 The priming fluid, usually gasoline, is contained in a suitable can furnished with the stove. This can is arranged to deliver a suitable quantity through a suitable spout. This not being a part of the invention, it is not shown. Suffice it to say that if one wishes to start the burner he simply lifts the gravity lid up over the lug q , where it will stay while the operator places the spout of the can into the funnel-like opening of the priming horn. A measured quantity of priming fluid may then be introduced and it will flow down through the elbow and the T into the outer annular vaporizing ring and also into the inner vaporizing channel. One may then apply a match to it and the priming fluid being a self-vaporizing fluid will ignite. This in a short time will heat up the vaporizing channel so that the needle valve o may be turned to allow the heavier fuel oil to run into the vaporizing rings.

The combined elbow and T is a single casting and supports itself independently of the stove top or frame. No slip joint is

required as with the previous funnel which had to be made detachable to permit cleaning. With the covered priming horn no cleaning should ordinarily be necessary.

What we claim is:

1. In an oil vapor stove, the combination of a burner provided with a vaporizer, a pipe leading into said vaporizer, a priming horn including a T having a pair of shoulders and into which the said pipe fits and is limited in its penetration by one of said shoulders, and a fuel oil connection secured to the other end of the T and limited in its penetration by the other of said shoulders, the priming fluid port in said T entering the T head between said two shoulders. 55 60 65

2. In an oil vapor stove, the combination of a burner provided with a vaporizer, a priming horn having a connection with said vaporizer and provided with an outer open end formed on a bevel and having a lid-supporting lug on the top and a gravity lid fulcrumed on said lid-supporting lug and having its center of gravity adapted to be swung over the vertical rising from said lug whereby the lid maintains itself in open 70 75 80 position. 85

3. In an oil vapor stove, the combination of a burner provided with a vaporizer, a fuel oil main, a fuel oil connection between said main and said vaporizer, and a priming horn connected with said fuel oil connection at an angle and turning substantially parallel therewith. 90 95

4. In an oil vapor stove, the combination of a burner provided with a vaporizer, a fuel oil main, a fuel oil connection between said main and said vaporizer including a T interposed in said fuel oil connection having the stem at substantially an angle therewith, and turning and running approximately parallel with said fuel oil connection. 95

5. In an oil vapor stove, the combination of a burner provided with a vaporizer, a priming horn connected therewith and provided with an outer beveled end, and a lid 100 acting as a closure for said beveled end.

In testimony whereof we affix our signatures.

JOHN S. SHERMAN.
ALVIN G. SHERMAN.
